UNITED STATES PATENT OFFICE.

FREDERICK SKELTON AND WALTER E. SKELTON, OF HAMILTON, ONTARIO, CANADA,
ASSIGNORS OF ONE-THIRD TO EDWARD W. McCARTY, OF NEW YORK, N. Y.

TOOL-HANDLE.

1,110,149.

Specification of Letters Patent.

Patented Sept. 8, 1914.

Application filed November 15, 1913. Serial No. 601,118.

To all whom it may concern:

Be it known that we, FREDERICK SKELTON and WALTER E. SKELTON, subjects of the King of Great Britain, residing at the city 5 of Hamilton, in the Province of Ontario and Dominion of Canada, have invented certain new and useful Improvements in Tool-Handles, of which the following is a full, clear, and exact description.

Our invention relates to handles for tools, such as shovels, spades, forks and the like, and particularly to that class of handles known as D handles, the ends of which are bifurcated and have a hand-grip member 15 extending across the top and joining the branches or forks.

Still more particularly our invention relates to that class of D handles having metallic bifurcated members which are secured 20 to the wooden stems and support the hand-grips. Such metallic members have a cylindrical socket for receiving the upper end of the wooden stem, and two oppositely branching arms extending from the upper end of 25 the socket and secured at their free ends to the respective ends of the cross hand-grip member.

The bifurcated members which are in general use are more or less unsatisfactory, being difficult to fit on the wooden stem, and being 30 expensive to manufacture, and being easily broken or bent, and the wooden hand-grips frequently splitting or becoming loose.

An object of our invention is to obviate 35 these disadvantages and to provide such a metallic bifurcated member which will be inexpensive and convenient to manufacture and strong and durable in use.

Other objects and advantages of our invention will appear from the following description.

In accordance with our invention, in order 40 to render the arms strong, we crimp or fold them longitudinally to form substantially 45 semi-tubular members or arms, and at the same time we turn the edges down against the sides of the arms, thereby making the arms of substantially a double thickness of metal at the parts which receive the greatest 50 strain. In order to provide a convenient means of attaching the hand-grip member and of securing it against splitting or getting loose, we provide a substantially cup-shaped part on the end of each arm into 55 which the respective end of the hand-grip

member is received, and is secured, preferably by a rivet passing through the handle and through perforations in the cup-shaped members.

Our invention also includes various other 60 features and details of construction as will hereinafter more fully appear.

We shall now describe the embodiment of our invention illustrated in the accompanying drawings and shall thereafter point out 65 our invention in claims.

Figure 1 is a perspective view of the end of a tool-handle embodying our invention; Fig. 2 is a central longitudinal section of the same; Fig. 3 is an elevation of a blank from 70 which the illustrated bifurcated member is made; and Fig. 4 illustrates a section of an arm on the line 4-4 of Fig. 2.

In the illustrated embodiment, the bifurcated member is made of a single piece of 75 suitable sheet-metal, preferably cold drawn sheet-steel, and is stamped and drawn by suitable dies and tools into the desired shape. As shown in Fig. 3, the blank consists of a generally rectangular oblong main 80 portion A, having two similar arms B extending from one of its longer edges and terminating in similar enlarged heads C. The rectangular portion A is bent into a cylindrical shape to form the stem-receiving 85 socket portion 1, into which the upper reduced end of the stem 2 is received and secured, as by rivets 3, which pass through the end of the stem and through perforations in the socket 1. The rectangular portion of 90 the blank is made of such length that the edges do not quite meet when bent to form the socket member, thereby providing a single longitudinal slit which permits the 95 diameters of the socket members to be varied to fit the particular stems and to compensate for variation in the diameters of the stems.

The arms B are so arranged that they are opposite to each other when the socket member is formed, and these arms are bent into 100 the usual curvilinear shape to form the arms 4 which constitute the bow of the D. These arms 4 are longitudinally crimped or folded into a substantial U shape in cross section, thus constituting semi-tubular shaped-arms. 105 More or less of the edges are turned inwardly and down against the inner sides of the arms as shown in Fig. 4, thereby affording a double thickness of metal throughout the length of the arms, while obviating the 110

raw exposed edge and providing a smooth engaging surface for the fingers. The reinforcing strip thus provided will prevent any longitudinal splitting of the handle 5 which frequently occurs when the socket is not thus reinforced at this point.

- The enlarged heads C on the ends of the arms B of the blank are utilized to form a substantially cup-shaped member 5 on the 10 end of each arm 4, which serves as a hand-grip receiving member. The usual wooden hand-grip 6 has its end tenoned or reduced in diameter, and these tenons are received into the cup-shaped members 5, and are secured therein as by a rivet 7, which passes through a longitudinal hole in the hand-grip and through perforations in the respective cup-shaped members 5. To prevent the hand-grip 6 from rotating in the cup-shaped 15 members, a plurality of indentations 8 are formed in the face of each cup-shaped member and are forced into the respective ends of the hand-grip and hold it against rotation. It will be noted that because of the 20 embrasure of the ends of the hand-grip for a substantial distance by the cup-shaped member 5, the hand-grip is firmly held and is prevented from splitting or from getting loose.
- 25 In order to afford all the strength available to the arms 4, the longitudinal crimping or folding is extended on the one end down along the sides of the socket 1 below the top thereof, and on the other end substantially 30 to the pivot-receiving perforations in the cup-shaped members 5. The arms are preferably made of a substantial width so that they may be bent to as great a curvature as is practical, the semi-tubular members thus 35 formed possessing great rigidity and strength which will permit them to withstand the severe usage to which the handle is subjected. The turned over edges may also be of a material width which will give the 40 desired additional reinforcement to the arms as well as a smooth edge for contact with

the fingers. The cup-shaped ends of the arms are easily formed and serve as caps for the ends of the hand-grip and provide extremely convenient and advantageous 50 means for engaging and securing the hand-grip. It will be manifest that the downwardly turned edges of the arms 4 may be turned outwardly instead of inwardly; and it is obvious that various other modifications 55 may be made in the construction shown and above particularly described, within the principle and scope of our invention.

Having described our invention, we claim:

1. A handle for tools comprising a 60 single piece of sheet metal having a cylindrical split lower portion, curved to form a stem receiving socket, two semi-tubular arms integral with and curving upwardly from the upper portions of the socket, the longitudinal edges of the semi-tubular arms and portions of the upper edge of the socket being folded inward against the adjoining surfaces of the arms and socket and forming continuous reinforcements from the end of one 65 arm to that of the other across the upper edge of the socket.

2. A handle for tools comprising, in combination with a stem and hand-grip, a bifurcated sheet-metal member having a stem-receiving socket provided with a single longitudinal slit, two arms integral with the socket and folded along substantially their central longitudinal lines and branching from the upper end of the socket and having 70 their longitudinal edges turned inwardly against their sides, and an inwardly open substantially cup-shaped member on the end of each arm adapted to receive and embrace the respective end of the hand-grip. 75

In witness whereof, we subscribe our signatures, in the presence of two witnesses.

FREDERICK SKELTON.
WALTER E. SKELTON.
